LOCK

Jalmar Polki, Chicago, Ill.

Application May 22, 1936, Serial No. 81,148

7 Claims. (Cl. 70—428)

This invention relates to locks and more particularly to key-operated locks.

One of the objects of the invention is to provide a key operated lock which cannot be unlocked with any key other than the one designed for it.

Another object of the invention is to provide a lock which practically cannot be picked with a wire or like implement.

10 Another object is to provide a lock having a plurality of tumblers in which the first tumbler blocks the keyhole when it is in its unlocked position, thereby preventing access to the other tumblers.

15 The above and other objects of the invention may be attained by providing a body portion having a bifurcated tumbler slidably mounted therein with its legs straddling a keyhole in the body portion. The legs are provided with overlapping ridges which normally lie out of register 20 with the keyhole but which are in register therewith when the tumbler is withdrawn into the body portion, thereby preventing insertion of a straight instrument into the keyhole. A key is 25 provided having a plurality of cam slots adapted to engage the ridges to cam the tumbler into the body portion, thereby unlocking the lock. If desired, a plurality of such tumblers may be provided, or tumblers of another type may be arranged back of the first tumbler, thereby making 30 it more difficult if not impossible to unlock the lock with anything other than the intended key. Preferably the tumbler or tumblers are retained in their locked position, i. e. the position extending outwardly from the body by means of spring-pressed latches which are released by insertion 35 of the key in the keyhole.

Other objects, advantages and novel features of the invention will be apparent from the following description when read in connection with the accompanying drawing, in which:

Figure 1 is a central section of a lock embodying the invention;

Figure 2 is an enlarged partial section on the line 2—2 of Figure 1;

Figures 3 and 4 are views of the opposite legs of the first tumbler of Figure 1;

Figures 5 and 6 are side elevations of Figures 3 and 4 respectively;

Figures 7 and 8 are elevations showing opposite sides of a key for use with the lock of Figure 1;

Figure 9 is a view similar to Figure 1 of a modified form of lock;

Figures 10 and 11 are elevations of opposite

sides of a key for use with the lock of Figure 9;

Figures 12 and 13 are views of opposite legs of one of the tumblers of Figure 9;

Figures 14 and 15 are similar views of the other tumbler;

Figure 16 is a central section of a further modified construction;

Figure 17 is a side elevation of the lock of Figure 16;

Figure 18 is an end view of Figure 16;

Figure 19 is a developed view of the tumbler of Figures 16 to 18; and

Figure 20 is a partial perspective of a door illustrating a manner of using the lock of Figures 16 to 19.

The lock of Figures 1 to 8 comprises an outer cylinder 21 adapted to be mounted in a door, a drawer or the like in the usual manner and having a plug or body portion 22 rotatably mounted therein, the plug 22 being formed with an elongated keyhole extending axially thereof. The cylinder 21 is formed with a pair of slots 23 and 24 to receive a tumbler 25 which is slidably mounted in the plug 22 and which is formed with a pair of legs 26 and 27 adapted to straddle the keyhole. The leg 26 as shown in Figure 3 is formed with a plurality of sloping ridges 28 and has a pin 29 secured thereto and lying below the ends of the ridges and the leg 27 is formed with a similar ridge 31 adapted to lie between the ridges 28 on the leg 26. The combined height of the ridges is preferably greater than the space between the legs so that a straight instrument cannot be inserted between the legs at that portion thereof on which the ridges are formed. The tumbler 25 is urged outwardly of the plug 22 by means of springs 32 having caps 33 to engage the end of the tumbler and arranged diametrically opposite to the slots 23 and 24.

A plurality of tumblers 34 are slidably mounted in the plug 22 rearwardly of the tumbler 25 in register with tumblers 35 which are slidably mounted in the cylinder 21 and urged toward the plug 22 by means of springs 36. The springs 36 normally urge the tumblers 35 and tumblers 34 toward the axis of the plug 22, the tumblers 35 at this time preventing relative rotation between the cylinder 21 and plug 22.

A key 37 is adapted to be used with the lock and as best seen in Figures 7 and 8 is formed with a single cam slot 38 on one side adapted to receive the ridge 31 on leg 27 and with a pair of grooves 39 on its other side to receive the ridges 28 on the leg 26. The end of the key is cut away as indicated at 41 to receive the pin 55

29 so that the key can slide freely into the key-hole until the pin 29 reaches the end of the cut-away portion 41 and engages the side of the first slot 39. Thereafter further movement of the key 5 into the keyhole will cause the tumbler 25 to be cammed downwardly by engagement of the ridges 28 and 31 in the slots 38 and 39, the pin 29 serving merely to engage the first cam slot 39 to move the tumbler 25 downwardly a sufficient 10 distance to cause the ridges 28 and 31 to engage in the cam slots. The end of the key is formed at one edge with a plurality of cam portions 42 which are of a correct height and space to cause the ends of tumblers 34 to lie flush with the 15 surface of the plug 22 when the key is inserted in the keyhole. If desired, the key may be formed with a longitudinal slot 43 to engage a corresponding projection on the side of the keyhole, thereby to prevent insertion of any except the proper key in the keyhole.

When the key 37 is inserted in the keyhole as indicated in Figure 1, the tumbler 25 will be withdrawn into the plug 22 and the ends of pins 34 will lie flush with the outer surface of said plug. At this time the key may be turned to turn the plug 22 in the sleeve 21, thereby to operate a suitable locking pawl in any desired manner. The slot 24 is provided in order to permit withdrawal of the key after the plug 22 has been turned, the slot preferably being located in such a position that it will register with the tumbler 25 when the plug 22 has been turned to a position to unlock the lock. With the plug 22 turned to this position the key may be withdrawn, the cam slots and the spring 32 serving at this time to force the tumbler 25 into the slot 24 to permit removal of the key and to prevent accidental turning of the plug 22.

According to another feature of the invention 40 a pair of spring-pressed latch members 44 are provided in the plug 22 adapted to engage notches 45 in the tumbler 25 to hold the tumbler in its position outwardly of the plug 22. These latch members, shown as consisting of two sets 45 of tumblers 47 and 48, preferably extend into the keyhole and are adapted to be cammed outwardly by insertion of the key, thereby to release the tumbler 25 to permit its withdrawal into the plug. This feature increases the difficulty of 50 withdrawing the tumblers by anything other than the intended key.

Figures 9 to 15 disclose a modified construction, parts therein similar to like parts in Figures 1 to 8, being indicated by the same reference numbers plus 100. In this form there are a pair of bifurcated tumblers 125 and 150 each formed with legs straddling the keyhole. The tumbler 125, as best seen in Figures 14 and 15, is formed with a pair of legs 126 and 127 carrying respectively a pair of ridges 128 and a single ridge 131. The pin 29 on leg 26 in Figures 1 to 8 is eliminated and the rearward ridge 128 is projected further down to have its end received in the cut-away portion 141 of the key until the key has moved sufficiently far into the lock for the edge of the rearmost cam groove 139 to engage the ridge 128. Further movement of the key into the lock thereafter will cam the tumbler 125 downwardly into the cylinder 122 in the same manner as described in connection with Figures 1 to 8.

The rearward tumbler 150 has a pair of legs 151 and 152, the leg 152 being provided with a single ridge 153 for reception in a cam groove 154 on the same side of the key as the grooves

139. The leg 151 has a pair of ridges 155 adapted to be received in cam grooves 156 on the opposite side of the key as best seen in Figure 10. This leg also carries a pin 157 adapted to engage the key substantially centrally of its height and the key is provided with a longitudinal groove 158 extending from the forward end thereof to the first cam groove 156 to receive this pin. The parts are so proportioned that the pin 157 will engage the side of the first cam groove 156 at the same time that the end of the rearward ridge 128 engages the rearward cam slot 139 so that both tumblers will be withdrawn simultaneously into the cylinder 122 as the key is thrust into the keyhole. The ridges on the tumbler legs in this form preferably overlap in the same manner as in Figures 1 to 8 so that when the front tumbler is withdrawn into the cylinder 122, it is impossible to force a straight instrument through it to engage the tumbler 150 to withdraw it into the cylinder. Thus it is substantially impossible to withdraw the tumblers by any instrument other than the particular key designed for the lock. It will be apparent that by varying the spacing of the ridges on the tumbler legs and by altering the vertical position of the pin 157, a substantially unlimited number of combinations can be obtained.

Figures 16 to 20 illustrate a very simple embodiment of the invention applied to a keyhole lock for preventing insertion of a key into the usual type of keyhole. This construction includes a body portion 160 of a shape to be received in a conventional keyhole as best seen in Figure 18. The body 160 is formed with an elongated keyhole slot 161 and slidably receives a tumbler 162 which is adapted to project outwardly of the body under the influence of a spring 163. As best seen in Figure 19 the tumbler 162 is formed of a single sheet of metal of I-shape adapted to be folded over at its center and having ridges 164 on its opposite legs which will lie facing each other in staggered relation when the sheet is folded. One of the legs also carries a pin 165 which will lie in register with the keyhole when the tumbler extends outwardly of the body 160.

A key 166 formed with a plurality of cam grooves 167 on its opposite sides is adapted to be used with the lock, the grooves 167 being formed to register with the ridges 164. The key also has a longitudinal slot 168 terminating in a short cam groove 169 to receive the pin 165. When the key is forced into the lock it will slide freely until the pin 165 reaches the cam groove 169, at which time the tumbler 162 will be cammed downwardly until the ridges 164 engage in the slots 167. Further movement of the key into the lock will cam the tumbler 162 into the body until the upper end of the tumbler lies flush with the outer surface of the body. At this time the body may be inserted in a conventional keyhole as indicated at 171 in Figure 20, and the key 166 may be withdrawn, thereby allowing the tumbler 162 to move outwardly of the body to lock the body in the keyhole. This will prevent insertion of a key, such for example as a skeleton key, in the keyhole and will prevent unauthorized persons from operating the door lock 172.

Preferably a spring-pressed latch member 173 is provided in the body 160 to engage notches 174 in the tumbler, thereby to lock the tumbler in its outward position. When the key is inserted in the lock its end will engage the latch member 173 and force it out of the notches 174, thereby to

permit movement of the tumbler. The key may, if desired, be provided with a spring latch 175 adapted to engage a projection 176 on the end of the body 160 so that when the tumbler 162 is withdrawn, the body 160 may be pulled out of the keyhole 171 by pulling on the key. When it is desired to remove the key and leave the body 161 in the keyhole, the operator may hold his finger against the body 160, thereby retaining it in the keyhole as the key is withdrawn.

While several embodiments of the invention have been shown and described, it will be apparent that many changes might be made therein or that various other embodiments might be devised. It is accordingly not intended that the scope of the invention shall be limited to the exact forms shown or otherwise than by the terms of the appended claims.

What is claimed is:

1. A lock comprising a body portion having a keyhole, a bifurcated tumbler slidably mounted in the body portion and having leg portions straddling the keyhole, projections formed on said leg portions, a spring pressed latch engageable with said tumbler to hold it in a position outwardly of the body portion and adapted to be moved out of engagement with the tumbler by a key inserted in the keyhole.

2. A lock comprising a body portion formed with a keyhole, a tumbler slidably mounted in said body portion, a pair of projecting ridges on said tumbler both projecting into the keyhole when the tumbler is in a retracted position, the innermost of said ridges extending farther inwardly in a direction parallel to the tumbler axis than the other, and adapted to engage cam slots in a key, said innermost ridge projecting into the keyhole when the tumbler is extended.

3. A lock comprising a body portion having a keyhole, a pair of bifurcated tumblers slidably mounted in the body portion each having legs straddling the keyhole, resilient means urging said tumblers outwardly of the body, said legs being formed with overlapping ridges of a combined height substantially equal to the width of the keyhole and normally lying out of register with the keyhole but in register with the keyhole when the tumblers are withdrawn into the

body whereby a straight instrument cannot be inserted in the keyhole.

4. A lock comprising a body portion formed with an elongated keyhole, a bifurcated tumbler slidably mounted in the body adjacent the inlet end of the keyhole and having legs straddling the keyhole, said legs being formed with overlapping ridges of a combined height substantially equal to the width of the keyhole and which are in register with the keyhole to prevent insertion thereinto of a straight instrument when the tumbler is withdrawn into the body, resilient means for urging the tumbler outwardly of the body, and a second tumbler slidable relative to the body into a locked or an unlocked position and remote from the inlet end of the keyhole.

5. A lock comprising a body portion formed with an elongated keyhole, a bifurcated tumbler slidably mounted in the body adjacent the inlet end of the keyhole and having legs straddling the keyhole, said legs being formed with overlapping ridges of a combined height substantially equal to the width of the keyhole and which are in register with the keyhole to prevent insertion thereinto of a straight instrument when the tumbler is withdrawn into the body, resilient means for urging the tumbler outwardly of the body, and a plurality of tumblers slidable relative to the body into a locked or an unlocked position and remote from the inlet end of the keyhole with their ends in register therewith.

6. A lock comprising a body portion formed with a keyhole, a tumbler slidably mounted in said body portion, and ridges on said tumbler extending into the keyhole and of such a height as to block insertion of a straight instrument into the keyhole when the tumbler is in a retracted position.

7. A lock comprising a body portion formed with a keyhole, tumbler means slidably mounted in said body portion and including parts lying adjacent each side of the keyhole, and overlapping ridges on said parts of a combined height substantially equal to the width of the keyhole to prevent insertion of a straight instrument into the keyhole.

JALMAR POLKI.
